The ornamental design for a combined desktop display and computer for intraoral scanner, as shown and described.

DESCRIPTION

FIG. 1 is a perspective view of a desktop display and computer for an intraoral scanner showing a first embodiment of our new design that includes a cradle for the intraoral scanner.

FIG. 2 is a second perspective view of the first embodiment thereof.

FIG. 3 is a front view of the first embodiment thereof.

FIG. 4 is a rear view of the first embodiment thereof.

FIG. 5 is a side view of the first embodiment thereof.

FIG. 6 is a side view of the first embodiment thereof.

FIG. 7 is a top view of the first embodiment thereof.

FIG. 8 is a bottom view of the first embodiment thereof.

FIG. 9 is a perspective view of a second embodiment of a desktop display and computer for an intraoral scanner. The front, side, top and bottom views of the second embodiment are the same as those of the first embodiment; and,

FIG. 10 is a rear view of the second embodiment thereof. The broken lines showing the table, cord and scanner in FIG. 9 are directed to environmental subject matters and are for illustrative purposes only, while all other broken lines are directed to portions of the combined desktop display and computer for intraoral scanner that form no part of the claimed design; the broken lines form no part of the claimed design.
